Geo. P. Kimmel
ATTORNEY.

UNITED STATES PATENT OFFICE.

FLORINDA GARDNER, OF TAMPA, FLORIDA, ASSIGNOR OF ONE-HALF TO MATTIE NUNN MASON, OF TAMPA, FLORIDA.

HANGER.

Application filed May 17, 1928. Serial No. 278,473.

This invention relates to a hanger and has for an object to provide, in a manner as hereinafter set forth, means for the expeditious suspension of a coat, hat, handbag, and 5 umbrella.

A further object of the invention is to provide a hanger of the class above referred to, which is particularly adaptable to be suspended within the body of an automobile, 10 thereby providing means for keeping hats, handbags and other articles off the seats and floor of the automobile for the better protection of such articles, the hanger being of collapsible construction in order to prevent 15 sent a more attractive appearance when not in use.

A further object of the invention is to provide a collapsible hanger as aforesaid, including as a part thereof a vertical supporting member which forms a protecting 20 shield for the other parts of the hanger when the same is suspended in folded position.

A further object of the invention is to 25 provide a hanger as aforesaid which is compact, readily portable, and comparatively inexpensive to manufacture.

Other objects and advantages will be apparent during the course of the following 30 description.

In the accompanying drawings in which like numerals are employed to designate like parts throughout the same,

Figure 1 is an elevation of a hanger constructed in accordance with this invention, 35 showing the same in partially folded position in dotted lines,

Figure 2 is an elevation of the embodiment shown in Figure 1, as the same is seen 40 from a right angle,

Figure 3 is a reduced view similar to Figure 1, showing a plurality of articles suspended on the hanger,

Figure 4 is an elevation of the hanger in 45 folded position, looking in the opposite direction to Figure 1,

Figure 5 is a detailed plan of the pivotal connection between the supporting member and arms.

In the drawings wherein for the purpose 50 of illustration is shown an embodiment of the invention, the numeral 1 designates a supporting member to which is pivotally connected a pair of arms, 2 and 3 respectively. The inner ends of the arms 2 and 3

are disposed in overlapping relation and are formed with transversely extending, aligned bores, through which extend a pivot pin 4. The pivot pin 4 also extends through a transversely bored spacing block 5, and through 60 a transverse bore provided in the supporting member 1. The spacing block 5 is interposed between the supporting member 1 and the arm 2, thus it will be seen that the arms 2 and 3 are connected together by the 65 pivot pin 4, and also pivoted to the supporting member 1 in spaced relation thereto. The arms 2 and 3 are formed with arcuate outer ends, as indicated at 6.

Pivottally connected to the arm 2, between 70 the transverse median and the outer end thereof, is a brace 7, which is free to swing about its pivotally connecting pin 8. The opposite end of the brace 7 is formed with a notch or recess 9, which is adapted to receive therein a stud 10 which projects forwardly from the forward face of the arm 3. The stud 10 and pin 8 are disposed at equal distances from the pin 4. When the arms 2 and 3 are in extended position as shown in 80 Figure 1, they are prevented from pivoting about the pin 4 by means of the brace 7 and the brace 7 is prevented from becoming displaced from the stud 10, longitudinally of the latter, by means of a supporting member 85 1 which extends across the outer face of the brace 7 in contact therewith. The notched end of the brace 7 is spaced from the arm 3 and may be pushed slightly inwardly to remove the frictional contact between the brace 7 and supporting member 1 when it is desired to disengage the notch 9 from the stud 10.

Secured to the outer face of the supporting member 1, by means of suitable holdfast devices 11, is a clamp 12. The clamp 12 consists of a pair of opposed members having spaced, parallel portions 13 and 14 respectively, which converge as shown at 95 15, and terminate in parallel jaw portions 100 16. The opposing faces of the members 13 and 14 are provided with ears 17 which are pivotally connected together. Disposed between the spaced parallel portions 13 and 14, is a coiled spring 18, the ends of which 105 respectively abut the inner faces of the portions 13 and 14. The upper ends of the clamp 12 and supporting member 1 terminate in the same horizontal plane, and a transverse bore extends through the mem- 110

bers 1 and 14 to receive therethrough a suitable hook 19, for suspending the hanger.

The lower end of the supporting member 1 is reduced and is formed with a hook 20, the free end of which is disposed upwardly. Spaced from the hook 20, the edges of the supporting member 1 are formed with annular pockets to receive therein the free end of a split annulus 21.

10 As clearly shown in Figure 3, the arms 2 and 3 are adapted to support thereon a coat 22, the clamp 12 is adapted to support a hat 23 by gripping the brim thereof, the hook 20 is adapted to have suspended thereon a 15 handbag 24, and the annulus 21 is adapted to receive therethrough and support the handle of an umbrella 25. The hanger may be used to support all or any one of said articles. When the hanger is not in use it 20 may be folded as shown in Figure 4, in which position the supporting member 1, brace 7 and arms 2 and 3 are in parallel relation and the hanger as a whole presents an attractive appearance. In folded position 25 the brace 7, and arms 2 and 3 are disposed rearwardly of the supporting member 1 and are protected thereby.

It is to be understood that the embodiment herewith shown and described is to be

taken as a preferred example of the same, 30 and that various changes in the size, shape and arrangement of parts may be resorted to without departing from the spirit of the invention or the scope of the appended claims. 35

What I claim is:

1. A hanger comprising a pair of arms, a brace pivoted to one arm and adapted for removable connection with the other arm, and a supporting member for pivotally supporting the arms and for holding the brace in position. 40

2. A hanger comprising a pair of arms having their inner ends pivoted together in overlapping relation, a brace pivoted to one arm and adapted for removable connection with the other arm, a supporting member to which the arms are pivotally connected, and a spacing block interposed between the supporting member and arms, said supporting member extending across the outer face of the brace to frictionally hold the latter in position to maintain the arms in opposed relation. 45

In testimony whereof, I affix my signature hereto. 50

FLORINDA GARDNER.
